UNITED STATES PATENT OFFICE.

WILLIAM M. MITCHELL, OF LOUISVILLE, KENTUCKY.

ANTICREEPER FOR RAILROAD-RAILS.

1,235,494.

Specification of Letters Patent.

Patented July 31, 1917.

Application filed March 31, 1917. Serial No. 158,791.

To all whom it may concern:

Be it known that I, WILLIAM M. MITCHELL, a citizen of the United States, and a resident of Louisville, county of Jefferson, and State 5 of Kentucky, have invented certain new and useful Improvements in Anticreepers for Railroad-Rails, of which the following is a specification.

The invention relates to anti-creepers or 10 rail anchors for preventing the creeping or longitudinal movement of railroad rails and seeks to provide a simple, inexpensive and effective anti-creeper or rail anchor which will remain solidly in position on the rail 15 under varying working conditions.

Rail anchors now in use, in order to avoid 20 perforating or otherwise weakening the rail, are held in position by a friction grip of one sort or another and are liable to work loose under the severe working conditions 25 to which they are subjected. The present invention seeks to overcome these difficulties and provide a rail anchor adapted to abut against the side of a tie and which is solidly 30 united to the rail by welding or fusing without weakening the metal body of the rail. The invention also seeks to provide a rail anchor of simple form which can be manufactured and installed at low cost. The 35 invention consists in the features of improvement hereinafter set forth, illustrated in the preferred forms in the accompanying drawings, and more particularly pointed out in the appended claims.

35 In the drawings:—

Figure 1 is a perspective view and

Fig. 2 is an end view of the preferred form of the present invention;

Fig. 3 is a side elevation of a modified 40 form; and

Fig. 4 is a plan view thereof.

The anchor shown in Figs. 1 and 2 is extremely simple and inexpensive and can be readily forged or shaped from a short section 45 of a flat bar of wrought iron or steel by twisting the same between its ends to form a depending, tie-engaging abutment 9 and a rail-engaging portion 10 at its upper end, which is arranged at right angles to and 50 in rear of the front, tie-engaging face of the abutment 9. The rail-engaging portion 10 of the anchor is adapted to be securely fused or welded to the edge portion of the rail base, and, preferably, is offset at its 55 upper end to thereby form a shoulder 11 which extends beneath the edge of the rail base. The intermediate twisted portion 12 serves as an inclined strengthening brace between the rail and tie-engaging portions of the anchor. 60

The form shown in Figs. 3 and 4 can be readily forged from a short section of round bar of wrought iron or steel and comprises a tie-abutting portion 5, an upwardly or rearwardly extending brace or body portion 6, and a rail-engaging portion disposed at right angles to the abutment 5, and comprising a shoulder 7 that extends beneath the edge of the rail flange and a lip 8 which extends over the vertical face of the rail 70 flange. This form can be shaped or forged, as stated, from a short section of a round bar by distorting or offsetting the opposite ends of the bar section to form the tie and rail-engaging portions which are connected 75 by the intermediate bracing or body portion.

Either form of the improved anchor can be readily secured to one of the base flanges of the rail by welding or fusing, and either 80 before or after the rail is placed in position in the track. Preferably, the anchor is applied to a rail already in place in the track, and when this is done, a portion of the base flange adjacent the tie is heated 85 nearly to the fusion point by suitable means, such as a portable oxy-acetylene torch. The anchor is then applied in position, and the adjacent engaging portions of the anchor and rail are fused together by aid of the 90 welding torch. Preferably, also, fillets of metal fused from a steel rod connect adjacent portions of the rail base and anchor, such fillets being solidly united or incorporated with the metal of the connected 95 parts. In this way, the anchor is solidly and permanently united with the rail without indenting or otherwise weakening the metal body thereof. Obviously, the anchor is permanently fixed to the rail so that it 100 cannot be dislodged by the expansion and contraction of the rail or by its movement away from the tie. Nor can the anchor be dislodged by the pounding and vibration, due to the passage of heavy traffic over the 105 rail. Preferably, as shown in Fig. 4, the portion of the anchor projecting outwardly beyond the edge of the rail base is provided with rounded fillets or portions which will engage and deflect the wheels of a derailed 110

car that might otherwise break off or destroy the anchor.

It is obvious that changes may be made in the details set forth without departure 5 from the essentials of the invention, as defined in the claims.

I claim as my invention:—

1. A one-piece rail anchor forged or shaped from a short section of substantially 10 straight bar by distorting or offsetting the opposite end portions thereof to form a depending tie-engaging abutment, an upper rail-engaging portion disposed substantially at right angles to said abutment and adapted 15 to be permanently fused or welded to one edge of the rail base, and an intermediate bracing or body portion between said abutment and said rail-engaging portion.

2. A one-piece rail anchor comprising a

metal bar twisted between its ends to form 20 tie-abutting and rail-engaging portions.

3. A one-piece rail anchor comprising a metal bar twisted between its ends to form tie-abutting and rail-engaging portions and having its upper end offset to provide an 25 upwardly projecting lip and an inwardly projecting shoulder.

4. A one-piece rail anchor shaped or forged from a short section of metal bar by 30 distorting or offsetting its opposite end portions to form a tie-engaging abutment, an upper rail-engaging portion and an intermediate bracing or body portion, said upper rail-engaging portion having an upwardly projecting lip and an inwardly projecting shoulder.

WILLIAM M. MITCHELL.
